PRODUCTION OF ODORLESS NAPHTHAS USING ANTIOXIDANTS

George W. Ayers, Chicago, and Walter J. Sandner, Carpentersville, Ill., assignors to The Pure Oil Company, Chicago, Ill., a corporation of Ohio

No Drawing. Application October 27, 1955

Serial No. 543,245

6 Claims. (Cl. 260—683.48)

This invention relates to a method of preparing odorless naphthas and, more particularly, to a method of distilling heavy alkylate or fractions thereof whereby the formation of odor in the distillates is prevented.

The problem of preparing naphthas, particularly from heavy alkylates or derived fractions, which are free of odor after treatment and also remain odor-free during storage over extended periods of time, has persisted for a long time. There are many processes disclosed in the prior art which relate to removing odorous materials from hydrocarbons and which may be classified as sweetening processes, wherein the various sulfur and oxygen compounds which cause some of the odor are chemically modified, removed or absorbed. The steps of these prior art methods, whether chemical or physical, when applied to alkylate fractions have been found to be inadequate for the removal of odor or the prevention of odor formation during storage.

Now, in accordance with the present invention, it has been found that the distillation of naphthas or heavy alkylates under reduced pressure with or without an inert gas, such as nitrogen or steam, in the presence of very small amounts of 4:4'-tetramethyldiaminodiphenylmethane and/or 2,6-di-tertiary-butyl para-cresol in the order of 1.0 weight percent or less during the distillation is sufficient for this purpose, and the uncertainty as to whether or not a product will be unsatisfactory is removed, thereby making the preparation of odorless naphthas a uniform and dependable operation. This invention does not relate to the removal of odor from naphthas or heavy alkylates which have already decomposed to the point of being odorous, but rather is directed to the prevention of odor formation during distillation of naphthas or heavy alkylates which are already essentially odor-free but have a decided tendency to go off-odor during storage. Consequently, those processes in the prior art which are concerned with the treatment of cracked naphthas, or naphthas containing sulfur compounds which are notoriously odorous, have no bearing on this disclosure. It has further been found that seam distillation or distillation in the presence of an inert gas under reduced pressure does not accomplish the desired result. Also, experiments were conducted wherein large amounts of 4:4'-tetramethyldiaminodiphenylmethane and/or 2,6-di-tertiary-butyl para-cresol were added to odorous naphthas and it was found that an odor-free naphtha was not obtainable. The prevention of odor, is therefore, a different problem from deodorization.

In carrying out the invention, very small amounts of 4:4'-tetramethyldiaminodiphenylmethane and/or 2,6-di-tertiary-butyl para-cresol may be used, namely from about 0.001 to 1.0 weight percent based on the weight of

2

naphtha charged. The distillation must be conducted under reduced pressure. In fact, although it is a very expensive expedient, distillation alone under a vacuum of 2 mm. of mercury may constitute a method of preventing odor formation, although the results obtained are not always consistent. Distillation alone at 10 to 15 mm. of mercury produces naphthas which are sometimes passable and sometimes not passable as far as odor is concerned. With small amounts of 4:4'-tetramethyldiaminodiphenylmethane and/or 2,6-di-tertiary-butyl para-cresol present, higher pressures can be used which are of the order of 75 to 115 mm. of mercury, preferably not more than 200 mm. of mercury for consistent results. The use of steam or other inert atmosphere allows the process to be carried out at a higher total pressure than would otherwise be allowable.

A primary object of this invention is to provide a process for preventing the formation of odor in naphthas during distillation.

Another object of this invention is to provide a method of preventing the formation of odor and insuring odor stability in heavy alkylate fractions by distilling in the presence of a small amount of 4:4'-tetramethyldiaminodiphenylmethane and/or 2,6-di-tertiary-butyl para-cresol under reduced pressure, with or without the presence of an inert gas.

Based on previous experience, it was found that not all compounds known to be inhibitors would function under the conditions of distillation normally applied to naphthas. It was established that certain phenols, cresols and even aniline, which have some inhibiting properties at room temperature, are not effective at the distillation temperatures, giving odorous products rated as not passable. All mono-, di-, and tertiary aliphatic amines, typical of which is triamylamine, which are well known color inhibitors for various products, are not satisfactory for purposes of producing odor-free and odor-stable naphthas or alkylates. Furthermore, no special petroleum fractions or derivatives, also possessing known inhibiting properties, are satisfactory for the present purpose. Petroleum phenols and tar acids, for example, do not give a product having passable odor upon distillation in accordance with this invention.

It was found, however, that the two inhibitors set forth herein when used under the conditions specified were very effective. The inhibitors found satisfy certain other requirements not otherwise shared by the numerous inhibitors tested. The boiling point of the inhibitor must be higher than that of the naphtha or alkylate being treated so that there is no carry-over with the hydrocarbon vapors leaving the vaporizing zone. The inhibitor must be essentially odorless in itself and stable at the distillation temperatures. Lastly, the inhibitor must be effective under the conditions of distillation.

In order to demonstrate the invention a series of experiments was conducted in which a sample of heavy alkylate produced by the hydrofluoric acid alkylation of isobutane with isobutylene was divided into a plurality of samples. This heavy alkylate exhibited the following distillation characteristics:

TESTS ON HF HEAVY ALKYLATE

Table I

API Gravity	Distillation													Odor			
	IBP	5%	10%	20%	30%	40%	50%	60%	70%	80%	90%	95%	E. P.	Per-cent Rec.	Per-cent Res.	Per-cent Loss	
54.0-----	347	354	356	358	360	363	366	369	374	383	414	466	517	98.0	1.6	0.4	slight (essentially odorless).

Example 1.—500 cc. of this heavy alkylate was placed in a flask with 0.04 gram of 2,6-di-tertiary-butyl para-cresol and the mixture was distilled at 110-120 mm. total pressure using 4.5 lbs. of steam per gallon of total distillate. The product, amounting to 375 cc., had practically no odor whatsoever and was satisfactory for use as an odorless mineral spirits.

Example 2.—500 cc. of this heavy alkylate was distilled in the presence of 1.9 grams of 4:4'-tetramethyl-diaminodiphenylmethane with steam under 50-55 mm. total pressure. A product amounting to 375 cc. of distillate was obtained which was satisfactory for marketing

inhibitors are not only odor-free after preparation but the odor stability is greatly enhanced as exhibited by extensive storage tests. This is shown by Table III in which various portions of the same heavy alkylate described in Table I prepared by separate distillations with the indicated amounts of various inhibitors or odor absorbing materials are used. Sample 13 is an odorless mineral spirits from an outside source. In each case the inhibitor remained in the still and was not present in the stored samples. Each determination is the result of two or more duplicate samples stored in glass bottles under air and in diffuse light for 70 days at room temperature.

Table III
ODOR STABILITY (ON STORAGE) OF ODORLESS MINERAL SPIRITS
[Samples stored in glass bottles under air and in diffuse light for 70 days at room temperature.]

Sample No.	Inhibitor Used	Amount of Inhibitor used (1% by Weight Based on the Naphtha)	Odor at Start of Test	Odor After Standing 70 Days
9.....	unwashed Odorless Mineral Spirits	(no inhibitor).....	slight (passable).....	very considerable (not passable).
10.....	Odorless Mineral Spirits washed with caustic soda soin, and water.	.....do.....	.....do.....	considerable (not passable).
11.....	2,6-Di-tertiary-butyl para-cresol	0.05.....	none to slight (passing).....	slight (passable).
12.....	Activated Alumina (finely divided)	0.05.....	slight (passable).....	appreciable (not passable).
13.....	Odorless Mineral Spirits (Calif.)	(no inhibitor).....	.....do.....	bad (not passable).

as odorless mineral spirits. This product is markedly superior from the odor standpoint to that produced by similar distillation of heavy alkylate containing no odor inhibitor.

In order to further demonstrate the invention, a series of distillations was conducted using different pressures, varying amounts of inert gas and varying amounts of 4:4'-tetramethyl-diaminodiphenylmethane and/or 2,6-di-tertiary-butyl para-cresol. The results are shown in Table II.

Table III shows that naphthas prepared without using inhibitors during the distillation develop unsatisfactory odors upon storage, even though the degree of odor present in the freshly prepared sample was considered passable. Also, other known odor inhibitors or odor removing techniques failed to exhibit proper storage stability. In contradistinction, naphthas prepared by using 2,6-di-tertiary-butyl para-cresol during the distillation remained acceptable on extended storage.

Although the invention has been demonstrated by

Table II
DISTILLATION OF A HEAVY ALKYLATE

Run No.	Dist. Pressure (mm. Hg)	Inert Gas used during Distillation	Inhibitor added to charge before Distillation	Max. overhead temp. during Distillation, ° F.	Max. bottoms temp. during Distillation, ° F.	Distillate Yield (Percent of charge)	Odor of Distillate
1.....	Atm.	steam (8.6 lbs. per gal. dist.)	none.....	222	242	75	(terpene-like) not passable. Do.
2.....	77-80	steam (2.6 lbs. per gal. dist.)	.....do.....	160	183	75	
3.....	2	nitrogen	.....do.....	134	150	75	almost odorless (passable). Do.
4.....	2	none.....	.....do.....	145	192	75	(slight odor) not passable.
5.....	100	nitrogen	.....do.....	252	273	60	almost odorless (passable).
6.....	50	steam (4.2 lbs. per gal. dist.)	4:4'-tetramethyl-diaminodiphenylmethane (0.5%).	146	164	75	extremely slight odor (passable)
7.....	111-122	.....do.....	2,6-di-tertiary-butyl para-cresol (0.5%).	177	195	75	almost odorless (passable).
8.....	109-115	steam (6.4 lbs. gal. of dist.)	2,6-di-tertiary-butyl para-cresol (0.01%).	159	180	75	

As shown in Table II, distillation alone, according to runs 1 and 2, with or without the application of a vacuum gives negative results. Runs 2 and 7, the former without inhibitor and the latter with 2,6-di-tertiary-butyl para-cresol present, show that under closely parallel temperature conditions the inhibitor carries the alkylate through the odor test. The main differences in operating conditions of the experiments of Table II are in the pressures and quantities of steam applied, but the relationships between these variables are such that the temperatures are essentially the same.

Another aspect of the invention is the discovery that naphthas or alkylates prepared by using the specified

reference to a certain alkylate fraction, such showing is not to be construed as limiting the scope thereof. It is considered that the invention will apply to all hydrocarbon mixtures from which naphthas are to be prepared for use as solvents, paint thinners and the multitude of applications for which odor-free and odor-stable materials are necessary. The discovery herein is of added interest because alkylate fractions, especially those boiling in the range of about 347° to 517° F. are particularly difficult to stabilize and tend to go off-odor-quickly on storage as indicated by Sample 9 of Table III. Other alkylates prepared from the reaction of a parafin hydrocarbon and an olefin using other known alkylation cata-

lysts, e. g., sulfuric acid or phosphoric acid, may be treated in accordance with this invention. The only limitations applying to the invention are expressed in the appended claims.

What is claimed is:

1. The method of preparing stable-odor-free alkylate fractions boiling within the range of about 347° to 517° F., said alkylate being prepared by the acid-alkylation of a paraffinic hydrocarbon and an olefin, comprising, distilling said alkylate at subatmospheric pressure in the presence of about 0.001 to 0.05 weight percent of an inhibitor selected from the group consisting of 4:4'-tetramethyldiaminodiphenylmethane and 2,6-di-tertiary butyl para-cresol and collecting an essentially odor-free, storage stable distillate.

2. The method in accordance with claim 1 in which the inhibitor is 4:4'-tetramethyldiaminodiphenylmethane.

3. The method in accordance with claim 1 in which the inhibitor is 2,6-di-tertiary-butyl para-cresol.

4. The method in accordance with claim 1 in which the pressure used varies from about 10 to 200 mm. Hg and about 25 to 200 weight percent of an inert, vaporizable diluent is present during the distillation.

5. The method in accordance with claim 4 in which the diluent is steam.

6. The method in accordance with claim 4 in which the diluent is nitrogen.
